UNITED STATES PATENT OFFICE.

HOYT RAYMOND, OF CHICAGO, ILLINOIS, ASSIGNOR TO VAUGHAN & BUSHNELL MANUFACTURING COMPANY, OF CHICAGO, ILLINOIS, A CORPORATION OF ILLINOIS.

DESIGN FOR A HAMMER-HEAD.

51,350.

Specification for Design.

Patented Oct. 9, 1917.

Application filed May 4, 1917. Serial No. 166,484. Term of patent 14 years.

To all whom it may concern:

Be it known that I, HOYT RAYMOND, a citizen of the United States, residing in the city of Chicago, in the county of Cook and State of Illinois, have invented a new, original, and ornamental Design for a Hammer-Head, of which the following is a specification, reference being had to the accompanying drawings, forming part thereof.

In these drawings Figure 1 shows the hammer head in side view; and Fig. 2 shows it as viewed from the top of Fig. 1.

I claim:

The ornamental design for a hammer head substantially as shown.

HOYT RAYMOND.
